DESIGN FOR A GOGGLE

Charles J. Haag, Carlstadt, N. J.

Application October 18, 1938, Serial No. 80,533

Term of patent 7 years

To all whom it may concern:

Be it known that I, Charles J. Haag, a citizen of the United States and resident of Carlstadt, in the county of Bergen and State of New Jersey, have invented a new, original, and ornamental Design for a Goggle, of which the following is a specification, reference being had to the accompanying drawing, forming a part thereof, and of which Figure 1 is a perspective view of a goggle showing my new design, Fig. 2 is a view thereof in front elevation, and Fig. 3 is a view thereof in side elevation.

The characteristic feature of the design resides

in the temples each having a wide front shade portion and a narrow rear portion, the top edge of the front portion being stepped downwardly to the top edge of the rear portion to a sufficient extent to cause the elevation of the rear portion at a point where it rests on the wearer's ear to be approximately in horizontal alinement with the center of vision of the goggle.

I claim:

The ornamental design for a goggle, substantially as shown and described.

CHARLES J. HAAG.
